UNITED STATES PATENT OFFICE.

WILLIS M. WILMORE, OF VAN WERT, OHIO.

DISPLAY-RACK.

No. 918,937.

Specification of Letters Patent. Patented April 20, 1909.

Application filed May 26, 1908. Serial No. 435,065.

To all whom it may concern:

Be it known that I, WILLIS M. WILMORE, a citizen of the United States, residing at Van Wert, in the county of Van Wert and 5 State of Ohio, have invented new and useful Improvements in Display-Racks, of which the following is a specification.

This invention relates to display racks, designed for the advantageous display for 10 merchandise of various kinds, the object of the invention being to provide a rack embodying a plurality of holders arranged in an endless series upon chains combined with operating and guiding shafts and sprocket 15 wheels together with means for imparting movement to said chains and propelling the carriers to a substantial elliptical path so that they will not interfere with each other in order to properly display the goods carried thereby.

A further object of the invention is to provide means whereby the carriers either with or without the goods thereon may be readily detached from the remainder of the 25 apparatus and reattached thereto.

With the above and other objects in view, the nature of which will more fully appear as the description proceeds, the invention consists in the novel construction, combination 30 and arrangement of parts as herein fully described, illustrated and claimed.

In the accompanying drawings:—Figure 1 is a vertical transverse section through a display rack embodying the present invention. Fig. 2 is a front elevation of the same. Fig. 3 is a vertical transverse section through a rack modified to adapt a portion thereof to be connected to a ceiling or overhead support. Fig. 4 is a front elevation of the 40 same. Fig. 5 is a side elevation of the rack especially adapted for carrying rolls of merchandise. Fig. 6 is a front elevation of the upper portion thereof, showing the sprocket wheels in section. Fig. 7 is a plan view 45 partly in section of one of the hanger rods or carriers. Fig. 8 is a similar view showing a slight modification. Fig. 9 is a perspective view of one of the chain links.

The rack frame is composed of a plurality 50 of standards 1 and 2 connected at their lower ends to a suitable base 3 and connected at their upper ends by cross bars 4. The frame as a whole may be constructed either of wood or metal or metal tubing as illustrated respectively in Figs. 1, 3 and 5, this not being essential as the construction of the

frame and the material of which the same is composed may be widely varied without departing from the principle of the invention.

In the preferred form of the invention, I 60 provide upper and lower sets of sprocket wheels 5 and 6 as shown in Fig. 1, the same being journaled on stud shafts 7 connected with the rack frame, 8 designating parallel chains which run around the sprocket wheels 65 5 and 6 in the manner illustrated in Figs. 1 and 2. Each of the chains is composed of links each comprising an open center rectangular body 8' provided at one end with a hook 9 adapted to engage the cross bar 10 70 of the adjacent length whereby the links may be readily disconnected from each other so as to enable the carriers or rods herein-after described to be set at the desired distance apart. Certain of the links are provided at opposite sides with outwardly projecting lugs 11 and 12 which are adapted to receive the journals of the carriers.

Where the display rack is to be used for the support of articles such as suits, hats, 80 shoes and the like, as shown in Figs. 1 and 2, certain of the rods or carriers 13 will have suspended therefrom trays or baskets 14 adapted to receive the smaller articles while alternate supporting rods or carriers 13 will 85 be supplied with coat hangers 15 adapted for the support of coats as indicated at 16, the trousers and vests adapted to be deposited in the baskets or trays 14 as will be readily understood by reference to Fig. 1. 90 By reference to Fig. 2, it will be observed that the supports or carriers for the baskets 14 are in the form of short rods or studs 17 from the inner ends of which the baskets are suspended so that the baskets will readily 95 pass by the sprocket wheels 5 and 6 at the top and bottom of the display rack.

The means for operating the movable parts of the rack may consist of a hand crank 18 upon the shaft of which is mounted 100 a sprocket wheel 19 from which a chain 20 extends upward around a sprocket 21 in a shaft 22 journaled in bearings at the top of the display frame, while another chain 23 passes around a sprocket wheel 24 on the 105 shaft 22 and around another sprocket wheel 25 on the shaft of one of the upper sprocket wheels 5. This provides for driving the chains, from the top which will be found more effective and practical in lifting the 110 articles by a pulling action on the chain rather than by a pushing action which would

follow the location of the driving mechanism at the bottom of the display frame so as to drive one of the lower sprockets instead of one of the upper sprockets.

- 5 Instead of the hand operating means hereinabove described, the removable parts of the display mechanism may be driven by a motor shown at 26 having a sprocket wheel 27 thereon from which a chain 28 passes 10 around another sprocket wheel 29 on the top shaft 22, motion being imparted from the top shaft 22 to one of the upper sprocket wheels 5 by which a short chain 30 running around a sprocket wheel 31 on the top shaft 15 and around another sprocket wheel 32 on the shaft of the sprocket wheel 5 as clearly shown in Fig. 2.

In lieu of the arrangement shown in Figs. 1 and 2, short floor standards 33 may be 20 used as shown in Figs. 3 and 4 while the upper sprocket wheels may be supported by ceiling hangers 34 adapted to be secured to a ceiling or other overhead support thus doing away with the standards 1 and 2 shown in Figs. 1 and 2. In like manner the 25 motor indicated at 26 may be mounted in a ceiling hanger 36 and motion communicated therefrom to one of the upper sprocket wheels by a driving belt 37 passing around 30 a pulley 38 on shaft of the motor and also around a larger pulley 39 on the shaft to one of the upper sprockets. In Figs. 2, 3 and 4 the top shaft is omitted so as to allow the use of the larger shelves indicated at 35 40 and instead of having two sets of upper sprocket wheels 5 as shown in Fig. 1, there may be a single set of sprocket wheels of larger diameter as shown at 41.

In Figs. 3 and 4, I have also shown means 40 for operating the rack by hand consisting of a hand operated crank 42 on the shaft to which is arranged a sprocket wheel 43 from which a chain 44 extends upward around another sprocket wheel 45 on the shaft of 45 one of the upper sprocket wheels 41.

Where the rack is intended for use in displaying rolls of merchandise, it is preferred to construct and arrange the same as shown in Figs. 5 and 6 for which it will be observed that single side standards 46 are employed connected at their lower ends to base board pieces 47. On account of the 50 relatively small diameter of the rolls of merchandise indicated at 48, the upper and lower sprocket wheels 49 and 50 may be made correspondingly smaller and in addition to extending the top shaft 51 across between the standards and upper sprocket wheels, a lower shaft 52 may be likewise extended 55 entirely across the frame between the lower sprocket wheels, thus enabling both sets of sprocket wheels to be mounted upon the respective shafts 51 and 52. The top shaft as shown is provided with an additional sprocket wheel 53 to which a chain 60

either from a hand power or motor driven device may lead for imparting motion to the movable parts of the display rack. In Fig. 5, I have shown a hand crank 54 having on the shaft thereof a sprocket wheel 55 70 from which a chain 56 extends upward around the sprocket wheel 53 for driving the mechanism by hand. It will be understood that a sprocket chain may be led from the wheel 53 to a suitable motor similar to 75 the arrangement shown in Figs. 1 and 2.

57 designates stay rods or braces interposed between the standards 46 and the base pieces 47 while 58 designates turn buckles for producing the desired tension 80 on said brace rods or stays.

In Figs. 7 and 8 I have shown the carriers in the form of rollers adapted to contain material in sheet form such as rugs, linoleum, oil cloth and the like, 59 designating 85 one of the rollers. In order to provide for readily attaching and detaching said carriers or rollers, each is provided with end journals 60 and 61 which are receivable in the lugs of oppositely located links 8.

Referring particularly to Fig. 7, it will be seen that a spring clip 62 is employed to prevent disengagement between the journal at one end of the roller and the adjacent link, said spring clip being shown as connected to 95 the journal and embracing one of the lugs of the adjacent link. However, said spring clip 62 may be connected to one of the lugs of the link as shown in Fig. 8, while the rear end thereof is adapted to engage over 100 a circumferential flange 63 on the adjacent end of the roller. The roller shown in Fig. 7 is of the spring type, and in the use of such a spring roller, the latter is provided at one end with a cylindrical socket 64 adapted 105 to receive the adjacent journal 61 which is in the form of a sliding spindle which passes through the lugs of the adjacent link and is pressed inward by a spring 65 which bears against a shoulder 66 on the journal 110 or spindle as clearly seen in Fig. 7. The journal or spindle 61 is further provided with an annular groove 67 into which extends the inner end of a spring pressed catch 68 carried by the roller 59 this locking the 115 journal and roller together while permitting the same to be readily disconnected for the purpose of removing the roller from the remainder of the apparatus. Where an ordinary roller is to be employed, or in other 120 words, a roller not provided with a spring to render the same self-winding, the spindle or journal 61', see Fig. 8, is connected to the adjacent end of the roller by screwing the same into the end of the roller as shown at 125 69, said journal or spindle being provided at its outer end with a hand crank 70.

Under either arrangement of carrier, the latter is adapted to be disconnected from the supporting and actuating chains, thus 130

providing for interchanging of the carriers and rendering it possible to use carriers of different kinds in connection with the supporting and actuating device. The construction described provides for a changeable display of merchandise in case of material such as rugs, linoleum, oil cloth, and the like provision is made for unrolling such material and rewinding the same upon 10 the respective rollers.

I claim:

A display rack comprising upper and lower sprocket wheels, parallel chains running around said sprocket wheels, and made 15 up of separable links each embodying an open center rectangular body, a hook at one end, and an outwardly projecting bearing

lug at one side, a plurality of carriers each embodying a shaft having end journals mounted in the lugs of oppositely arranged 20 links, means providing for detaching each carrier from the links involving a slidably journal, a spring acting to hold said journals pressed toward the carrier, and a spring-pressed key on the carrier engaging 25 an annular groove in the carrier, and means for imparting simultaneous and equal movement to said chains.

In testimony whereof I affix my signature in presence of two witnesses.

WILLIS M. WILMORE.
